CLAIM

The ornamental design for a mini blind cleaner, substantially as shown and described.

DESCRIPTION

FIG. 1 is a side elevational view of a mini blind cleaner, showing our new design;

FIG. 2 is a top plan view thereof;

FIG. 3 is a bottom plan view thereof;

FIG. 4 is a side elevational view of a mini blind cleaner as it appears when opened;

FIG. 5 is a left end elevational view of the mini blind cleaner as shown in FIG. 1;

FIG. 6 is a right end elevational view thereof.
